UNITED STATES PATENT OFFICE.

JAMES GRANT DAVIDSON AND ROBERT WILLIAM FORD, OF VANCOUVER, BRITISH COLUMBIA, CANADA.

PROCESS FOR IMPROVING THE QUALITY AND YIELD OF HYDROCARBON GASES.

1,229,042.

Specification of Letters Patent. Patented June 5, 1917.

Application filed November 29, 1915. Serial No. 64,115.

To all whom it may concern:

Be it known that we, JAMES GRANT DAVIDSON and ROBERT WILLIAM FORD, subjects of the King of Great Britain and Ireland, and residing at Vancouver, in the county of Vancouver and Province of British Columbia, Canada, have invented a new and useful Process for Improving the Quality and Yield of Hydrocarbon Gases, 10 of which the following is a specification.

We have discovered that by subjecting a gas or vapor containing a hydrocarbon or hydrocarbons, such as illuminating gas, or other gas produced by the destructive distillation of coal or petroleum or other methods of manufacture or production, to the action of a high tension electric discharge under certain conditions, a considerable change may be effected in the final 20 product, indicating a change in the constitution thereof; namely, an increase in the proportion of fixed gases in the total final product, and an increase in the volume of gas produced. Our invention is based on 25 this discovery.

An important object of our invention is to increase the percentage of fixed hydrocarbons in illuminating or similar gases, this object being attained in our invention 30 by breaking up condensable constituents into substances of less molecular weight and less condensability.

Another object of this invention, incidental to the above, is to increase the volume 35 of gas produced.

The accompanying drawings illustrate apparatus suitable for carrying out our invention, and referring thereto:—

Figure 1 is a vertical section of one form 40 of such apparatus, especially adapted to apply a surging high tension current to electrodes in contact with the gas to be treated.

Fig. 2 is a vertical section of another 45 form of apparatus showing a different form of current controlling means in the high tension circuit.

Fig. 3 is a vertical section of another 50 form of the apparatus, adapted to subject the gas to the action of a purely "static" discharge.

Referring to Fig. 1, the apparatus there- 55 in shown comprises a conduit 1, formed as a vertical pipe, connected at its lower end to

a gas supply pipe 2 and at its upper end to 55 an outlet pipe 3, whereby the gas to be treated may be conducted through said conduit. Said conduit is preferably of metal, and serves as one electrode of the discharge apparatus, the other electrode consisting, 60 for example of a wire 4 hung from an insulating support 5 at the top of the conduit 1 and extending axially in said conduit, said wire being tensioned by weight 5' or otherwise. 65

The electrode 4 is connected with high tension electric current supply means, consisting of a step up transformer 6, having its primary winding connected to an alternating current supply circuit 16, and its 70 secondary winding connected at one side to ground at 14 and at its other side to a current controlling device 8, from which a wire 7, leads to the electrode 4. Conduit 1 is grounded as indicated at 15. Said current 75 controlling device is here shown as of the form disclosed in the application of E. R. Wolcott and F. Rieber, filed August 3rd, 1914, Ser. No. 854,693 and comprises a plate electrode 10 and a pointed electrode 9, opposite 80 said plate electrode and surrounded by a tube 11, having an orifice 11' between said electrodes; said tube being connected by pipe 12 to a pump 13, whereby air or other gas may be forced into the tube and 85 through the orifice 11', thereby producing a blast of gas in the direction of the discharge between the electrodes 9 and 10. The primary effect of this blast on the discharge between the electrodes 9 and 10 is 90 to cause more or less rectification of the high tension alternating current supplied thereto from the transformer 6, by stopping, more or less completely, the current impulses in one direction and permitting 95 the impulses in the opposite direction to pass more freely, but another effect of this current controlling device is to cause more or less violent surging or oscillation of the current. We have found that with a device of this character included in the circuit of the apparatus good results may be obtained in the treatment of hydrocarbon gases according to our process. 100

Our process may be carried out in the above described apparatus as follows:

The gas to be treated, which may be ordinary illuminating gas at any stage of its

manufacture, but preferably at a stage preceding the washing and scrubbing operations, is led through the conduit 1, and is therein subjected to the action of a high tension silent electric discharge between the electrode 4 and the wall of said conduit. We have found that the constitution of the hydrocarbon constituents in the gas while in process of manufacture may be materially changed by the action of the electric discharge, the general effect of the discharge being to cause a breaking up of such constituents into constituents of less molecular weight, which are not condensable under working conditions, and, hence, to increase the proportion of fixed hydrocarbon constituents of the gas as compared with the other constituents, such as hydrogen, carbon monoxid, etc., and to increase the volume of gas produced. In actual tests we have by this process increased the amount of CH_4 in the gas from about 25% to approximately 40%, while the amounts of C_nH_{2n} were increased from between 7% and 10% up to between 20% and 23%.

In carrying out our invention on a commercial scale, the apparatus shown in Fig. 2, which is similar to that heretofore used for electrical precipitation of suspended matter from gases, may be employed. In this apparatus, the gas is conducted through a plurality of conduits formed as vertical pipes 21, connected at their lower ends to supply header 22 and at their upper ends to outlet header 23, the discharge electrode 24 being formed as wires hung axially in said pipes from insulated support 25. The pipes 21 are grounded as at 26 and the electrodes 24 are connected by wire 27 to a current modifying means 28 which may be a device such as shown at 8 in Fig. 1, or may be a mechanical rectifier of the usual rotary type, included in the high tension circuit of a step up transformer 30, said rectifier having a ground connection 31. The rotor 34 of the rotary rectifier 28 is driven in synchronism with the alternating current in usual manner and the stator contacts of the rectifier may be placed so as to interrupt the circuit at any desired phase relation. By this means we are enabled to break the circuit under conditions which may cause more or less surging, to increase or decrease the amount of surging, as desired. Our invention may be carried out in this apparatus substantially as above described, the circuit controlling means 28 being preferably adjusted to produce considerable surging of the high tension current, so as to increase to a maximum the amount of change produced in the gas being treated.

Our invention may also, in some cases, be carried out by applying alternating current 65 from an alternating circuit or from a trans-

former, directly to the gas to be treated, without the use of any current modifying means. Thus, as shown in Fig. 2, the current from transformer 30 may be conducted to the discharge electrodes 24, by closing 70 a switch 36.

Our invention may also be carried out by subjecting the gas to the action of a purely "static" discharge, for example in the apparatus shown in Fig. 3, consisting 75 of a tube 40 of glass quartz or like material, within which extends axially a discharge electrode 41, said tube being surrounded by a conductor 42, and the electrode 41 and conductor 42 being connected 80 to opposite sides of a high tension circuit. Said high tension circuit may include a current controlling device 44 similar to the device shown at 8 in Fig. 1, for modifying the high tension alternating current from 85 a transformer 45, or if desired, said device may be cut out by a switch 43 and the wire 46 leading to electrode 41 may then be in direct connection with one side of said transformer, the other side of the transformer being grounded at 47 and the conductor 42 being grounded as indicated at 90 48. In carrying out our invention in this apparatus the gas is passed through the tube 40, by supply and outlet connections 95 50 and 51, and is subjected in said tube to the action of a purely "static" discharge. If the switch 43 is closed the discharge will be simply that due to the high tension alternating E. M. F. impressed on the electrode 100 members 41 and 42 by the transformers; but by opening said switch the current may be modified so as to be surging or oscillatory in character as well as more or less rectified.

The breaking up or cracking of the hydrocarbons is effected according to our invention directly by energy supplied from the electrical current, the effect of the process as above described being to produce 110 energy in the gas at a sufficiently rapid rate and under such conditions as to break up some or all of the molecules of the hydrocarbons into molecules of hydrocarbons of less molecular weight.

What we claim is:

1. The process of treating a gas containing hydrocarbons which consists in subjecting it to the action of a high tension silent electrical discharge, in such manner as to 120 convert hydrocarbon constituents in the gas into constituents of less molecular weight and less condensability, the energy required for such conversion of the hydrocarbon constituents being derived directly from the 125 electrical discharge.

2. The process of treating a gas containing hydrocarbons which consists in subjecting it to the action of a high tension silent electrical discharge, in such manner 130

as to break up hydrocarbons in the gas into hydrocarbons of less molecular weight and less condensability, the energy required for so breaking up hydrocarbons in the gas being derived directly from the electrical discharge.

3. The process of treating a gas containing hydrocarbons which consists in subjecting it to the action of a high tension silent ¹⁰ electrical discharge to change the constitution of the hydrocarbons by means of the energy of such electrical discharge, in such manner as to increase the final volume of

the gas produced from a given amount of material.

4. The process of treating a gas containing hydrocarbons which consists in passing it between electrodes and applying to such electrodes a surging high tension electric current, in such manner as to change the ²⁰ constitution of the gas by the energy of the electric discharge and to increase the percentage of fixed hydrocarbon constituents therein.
